[57] ABSTRACT

A method of knitting an unroveable set-up comprising starting courses for a piece of fabric to be knitted on the single bed of needles of a knitting machine comprising the steps of knitting a first course and holding it against unroving, knitting at least one subsequent starting course, pulling alternate loops of said subsequent starting course through alternate loops of said first starting course and retaining the remaining loops of said subsequent starting course on the needles with the remaining loops of said first starting course, knitting a final starting course, and pulling alternate loops of said final starting course through said retained loops of the previous courses, and releasing said hold on the first starting course, leaving at least said first and final starting courses interlaced.

METHOD OF KNITTING

This is a continuation of application Ser. No. 197,288, filed Nov. 10, 1971 and now abandoned which was a continuation-in-part of application Ser. No. 33,375, filed Apr. 30, 1970 and also now abandoned.

This invention relates to the knitting of plain knit fabric, that is fabric knitted on needles of a single bed of needles, and is concerned with the provision of an unroveable set-up for a piece of such fabric.

Starting courses to produce an unroveable set-up are already known for rib-fabrics and can also be produced for plain knit fabric on machines which have web-holding sinkers. Initial courses of yarn can then be placed on the needles in a tuck-miss configuration before knitting an all-knit starting course having loops intermeshed by the initial courses of yarn which thus prevent the all-knit course from unroving.

The present invention provides a method of knitting starting courses for a piece of plain knit fabric which can be carried out on machines without web-holding sinkers, for example on fully-fashioned and flat bed knitting machines.

According to the invention a method of knitting, on a single bed of needles of a knitting machine, an unroveable set-up comprising starting courses for a piece of fabric to be knitted on the machine, comprises the steps of knitting a first starting course and holding it against unroving, knitting at least one subsequent starting course, pulling alternate loops of said subsequent starting course through alternate loops of said first starting course and retaining the remaining loops of said subsequent starting course on the needles with the remaining loops of said first starting course, knitting a final starting course, and pulling alternate loops of said final starting course through said retained loops of the previous courses, and releasing said hold on the first starting course, leaving at least said first and final starting courses interlaced.

The said first starting course may have its sinker loops held by a preliminary course consisting of an all-knit course of a draw-thread or waste yarn or consisting of the end of a previous piece of fabric.

Alternatively, in a knitting machine capable of knitting a first starting course on empty needles of a single bed of needles, no preliminary course need be knitted, the sinker loops of the first starting course then being held in the machine otherwise than by a preliminary course. For example, a take-down mechanism including a known welt-turning bar of the kind incorporated in many fully fashioned knitting machines may be used. Such bars carry a separate hook for engagement with each sinker loop. They can be used for knitting turned welts in a well-known manner, for example in knitting stockings on fully fashioned machines. It is also known to use welt bars for knitting welts which are not turned. In such cases, knitting is started on empty needles and after the first course of yarn has been laid in the needles, the welt bar is brought in to engage one of its hooks with each sinker loop. The take-down mechanism moves the welt bar away from the needles during subsequent knitting until a point is reached at which the welt hooks are disengaged from the fabric and the usual take-down hooks are engaged in the fabric to effect further take down.

Hitherto, such mechanisms have been used to knit roveable first courses, but they can also be used to knit

non-roveable set-ups according to this invention. When using such a take-down mechanism in the method of the invention, knitting is started on empty needles and each sinker loop of the first course is engaged by a hook of the welt bar as described above. The welt bar is used to pull the knitted fabric away from the needles during the first few courses of knitting until the set up is complete and another take-down means has engaged the fabric. A mechanism of this general kind could 10 equally well be used in V-flat machines as in fully fashioned machines.

If preliminary courses are used, which would be the conventional method of starting knitting on a single bed of needles, the invention can be carried into effect 15 on conventional knitting machines for example, circular, fully fashioned or V-bed machines. The invention is useful on V-bed machines when it is desired to knit fabric in tubular form, that is to knit pieces of flat fabric on each of the two opposed needle beds the pieces being joined at their edges to form a tube. This is a conventional procedure on such machines.

The invention extends to the knitting of starting courses for such tubular knitting.

Preferably, a plurality, for example two to five or 20 more of the said subsequent starting courses are used in order to produce a good bulk of yarn interlaced with the final starting course.

After the knitting of a subsequent starting course immediately preceding the final starting course, alternate 25 needles may be raised to knit height and to tuck height thus casting off stitches in alternate wales but retaining the remaining loops on the needles. The final starting course is then knitted, alternate loops of this course being pulled through any retained loops.

The first starting course may be a knit-tuck course. However, the first mentioned starting course is preferably an all-knit course.

The final starting course may contain tuck stitches in 30 wales other than those containing the said retained loops. However, the facility to produce a series of knit-tuck or knit-miss stitches followed by a series of tuck-knit stitches is not to be found on all machines and this facility is essential if the final starting course is to contain tuck stitches.

The starting courses, except for the final starting course, are preferably knitted of elastomeric yarn or 35 yarn which will relax (i.e. shrink) on subsequent treatment.

The invention includes plain knit fabric having starting courses knitted by the method described above and garments including such fabric.

The invention will be further described, by way of example, with reference to FIGS. 1 to 5 of the accompanying drawings which illustrate different methods according to the invention of knitting starting courses for plain knit fabric.

Referring to FIG. 1A, course *a* is the last course of a 40 piece of plain knit fabric and course *b* is a course knitted with a draw thread separating the course *a* of the previously knit fabric from the starting courses for a new piece of fabric. Course *b* is an all-knit course, that is in each wale of the knitting a loop of the course *b* is pulled through a previously formed loop.

The first starting course *c* of the new piece of fabric 45 is also in the present case an all-knit course in that in each wale a loop of this course is pulled through a loop of the draw thread course *b*. However, the next course

d is a knit-tuck course, the loops of course *d* in wales *y* are held in the needle hooks together with loops of the course *c*. The following course *e* is also a knit-tuck course and the loops of this course in wales *y* are taken into the needle hooks together with loops of course *d* and the still held loops of the first starting course *c*.

The final starting course *f* which completes the set-up is an all-knit course in the present instance and in wales *x* loops of course *f* are pulled through the heads of loops of course *e*. In wales *y*, loops of course *f* are pulled through loops of courses *c*, *d* and *e*. Thus loops of the first starting course are connected directly to loops of a subsequent starting course not lying immediately adjacent to it in the fabric.

After the final starting course *f* has been formed, the knitting of the piece of fabric is continued with course *g* and subsequent courses.

When the draw thread course *b* is removed, as shown in FIG. 1B, the sinker loops of course *c* can be pulled through the sinker loops of course *d* and the sinker loops of course *d* can then be pulled through the sinker loops of course *e*. This leaves the yarn of courses *c*, *d* and *e* in the configuration shown in FIG. 1B in which courses *c* and *d* are interlaced with loops of the final starting course *f* and prevent these loops from unroving. The sinker loops of course *e* can be pulled through the sinker loops of course *f* to lie beneath the fabric, as shown in FIG. 1B, together with the needle loops of this course. After removal of the draw thread *b*, therefore, course *e* is no longer locked into the fabric and can be pulled away.

Additional knit-tuck courses corresponding to additional courses *d* can be included to increase the bulk of the yarns interlaced with the loops of course *f* or course *d* can be omitted altogether if it is deemed sufficient to have one yarn only interlaced with the loops of course *f*. Preferably, courses *c* and *d* are knitted of elastomeric yarn so that on removal of the draw thread the tendency of the yarn to relax will pull these courses to the configuration shown in FIG. 1B.

Alternatively, courses *c* and *d* may be knitted from yarn which will relax on subsequent treatment such as washing and dyeing or a heat treatment.

Course *e* is preferably knitted from a yarn which is easily distinguished from that of courses *c*, *d* and *f* to enable this course to be recognised and pulled out of the fabric.

If course *a* is the last course of a previous piece of fabric, it may be locked during knitting to prevent unroving.

FIG. 2A illustrates another method according to the invention of forming starting courses for plain knit fabric.

Course *a* is the last course of previous knitting, course *b* is an all-knit draw thread course and course *c* is the first starting course and is an all-knit course. Courses *d* and *e* are knit-tuck courses as in FIG. 1 but course *f*, the final starting course, has a different configuration from course *f* of FIG. 1 and is a tuck-knit course. The result is that on removal of the draw thread as shown in FIG. 2B, courses *c* and *d* remain interlaced with loops of course *f* and course *e* is interlaced with course *f* and with the subsequent course of knitting *g* and is not free to fall out of the fabric.

Again, loops of the first starting course which are held during knitting of subsequent starting courses are connected directly to loops of the final starting course,

course *f*, so that on removing the draw thread, the yarn of the first starting course remains interlaced with the loops of the final starting course.

In FIGS. 3A and 3B, in which like reference letters are again used for the same courses as in FIGS. 1 and 2, an all-knit draw thread course *b* is followed by an all-knit first starting course *c*. This is followed by a knit-tuck course *d* and then a knit-miss course *e* in which yarn is floated across wales *y*. The final starting course *f* is an all-knit course having loops pulled through, and thus directly connected to, loops of the first starting course *c*.

On removing the draw thread *b*, as shown in FIG. 3B, courses *c*, *d* and *e* are left interlaced with loops of the final starting course *f*, as shown, preventing these loops from unroving.

FIGS. 4A and 4B show starting courses knitted in a similar manner to those of FIG. 3 except that the final starting course *f* is in this case a tuck-knit course. When the draw thread *b* is removed, courses *c* and *d* remain interlaced with loops of the final starting course *f*, as shown in FIG. 4B, and course *e* remains interlaced with loops of courses *f* and *g*.

FIGS. 5A to 5C show starting courses comprising a first starting course *c* joined as an all-knit course to an all-knit draw thread course *b*. Course *a* is the last course of the previous knitting. Starting course *d* is a knit-tuck course on alternate needles, the needles being indicated at *N* in FIG. 5A. A number of knit-tuck starting courses similar to course *d* can be knitted up to the limit of the tuck holding capacity of the needle hooks. Loops of course *c* in wales *y* are thus held on the needles. Following the last course *d* the needles reoperated to raise alternate needles to knit height and tuck height but no yarn is laid in. The loops of the last course *d* in wales *x* (the knit wales) are thus cast off the needles whereas the loops in wales *y* are retained in the needle hooks. The previous starting course loops in wales *x* thus unrove and drop out. If course *a* is the last of a number of courses of waste yarn, no special steps need to be taken to prevent unroving going beyond this course, but if course *a* is the last course of a previous piece of fabric a locking course may be included to prevent unroving going beyond course *a*.

Next, the final starting course *f* is knitted as an all-knit course to complete the set-up. Course *g* is the first course of subsequent knitting. The structure is now as shown in FIG. 5B.

When the draw thread *b* is removed, course *c* is released and courses *c* and *d* adopt the configuration shown in FIG. 5C interlaced with loops of the final starting course *f*.

As in the case of the set-up illustrated in FIG. 1, in the set-ups of FIGS. 2, 3, 4 and 5, courses *c* and *d* are preferably knitted from elastomeric yarn or yarn which will relax when suitably treated. Course *d* can be multiplied in all cases to increase the number of yarns interlaced with course *f* when the draw thread is removed.

Course *c* can be formed as a knit-tuck course instead of an all-knit course as shown in FIGS. 1 to 5.

The starting courses may be preceded by courses of waste yarn which may be the first courses of a length of fabric or may constitute separating courses between pieces of fabric. The draw thread course *b* would then be replaced by a course of waste yarn and instead of pulling out a draw thread to reveal the set-up it would be necessary to unrove the courses of waste yarn.

The present method of knitting starting courses is of particular use when knitting mock rib edge trims for garment panels produced on a fully fashioned knitting machine. Such machines do not normally have web-holding sinkers and thus the use of conventional set-up courses is precluded. Hitherto it has been the practice to knit edge trims of true rib fabric on a separate knitting machine and then to transfer these to the needles of the fully fashioned machine. The presence of the rib edge trims made it possible to commence plain knitting immediately on the fully fashioned machine without using special starting courses.

The present method of forming such courses enables entirely plain knit fabric pieces with acceptable edges to be produced on a fully fashioned knitting machine. A mock-rib construction at the edge of the garment involving a knit-tuck construction in course *g* and subsequent courses can then be used to produce a garment panel very similar in appearance to a conventional panel with a trim of true rib knitting.

What is claimed is:

1. A method of knitting on needles of a single bed of a knitting machine, an unroveable set-up comprising starting courses for a piece of fabric to be knitted on the machine, said method comprising the steps of
  - a. knitting a first starting course by taking yarn into the hooks of all of said needles and holding said first starting course against unroving,
  - b. knitting at least one subsequent starting course by taking yarn into the hooks of all of said needles, pulling alternate loops of said subsequent starting course through alternate loops of said first starting course and retaining the remaining loops of said subsequent starting course on the needles with the remaining loops of said first starting course,

- c. knitting a final starting course by taking yarn into the hooks of all of said needles, and pulling alternate loops of said final starting course through said retained loops of the previous courses, and
- d. releasing said hold on the first starting course, leaving at least said first final starting courses interlaced, thus to prevent unroving of said final starting course.

2. A method as claimed in claim 1 including knitting two to five subsequent starting courses between the first starting course and the final starting course.

3. A method as claimed in claim 2 in which at least one of the subsequent starting courses has alternate missed stitches in those wales in which another subsequent starting course has loops retained on the needles.

4. A method as claimed in claim 1 in which the remaining loops of the final starting course comprise tuck stitches.

5. A method as claimed in claim 1 wherein the starting courses, except for the final starting course, are knitted of elastomeric yarn or yarn which will relax on subsequent treatment.

6. A method as claimed in claim 1 in which prior to the knitting of the final starting course, the pulled through alternate loops of the subsequent starting course which immediately precedes the final starting course, are cast off whilst remaining loops thereof are retained on the needles.

7. A method as claimed in claim 1 including knitting a preliminary course before the first starting course for said purpose of holding the first starting course against unroving, and subsequently removing the preliminary course from the setup for said purposes of releasing said hold on the first starting course.
